UNITED STATES PATENT OFFICE.

MAX BUCHERER, OF COLOGNE, GERMANY.

SPRAY-CARBURETER.

1,097,165.

Specification of Letters Patent. Patented May 19, 1914.

Application filed July 8, 1913. Serial No. 777,895.

To all whom it may concern:

Be it known that I, MAX BUCHERER, a subject of the Emperor of Germany, and a resident of Cologne-on-the-Rhine, Germany, have invented certain new and useful Improvements in Spray-Carbureters for Explosive-Engines, of which the following is a specification.

This invention relates to improvements in spray carbureters for use with explosive or internal combustion engines in which besides the main nozzle an auxiliary nozzle is provided. The main nozzle or the main spray nozzle, respectively, is connected in the customary manner with a receptacle containing the liquid fuel as well as a float in the same, this liquid fuel is under atmospheric pressure, however, the liquid fuel for the auxiliary nozzle contained in a second receptacle, also provided with a float is under a different pressure from that prevailing in the suction pipe. Besides these two nozzles, a third nozzle is provided which is connected with the atmosphere. The exit port of the auxiliary fuel nozzle, or spray nozzle is arranged over the exit port of said third nozzle or air nozzle, corresponding to the nozzle arrangement of an inhalation device, so that the jet of air escaping from the last mentioned nozzle under the sucking action of the motor sucks like an injector from the auxiliary nozzle a corresponding quantity of additional fuel. This arrangement offers the great advantage that the carbureter works with two fuel nozzles which are entirely independent from one another, one of which however, the auxiliary fuel nozzle, is regulated with respect to the quantity of fuel it supplies, because the pressure existing within the receptacle belonging to that nozzle may be varied by means of an admitting screw. If the quantity of the liquid fuel supplied by the main nozzle becomes smaller, owing to clogging up or for other reasons, while the motor is running, or if the main nozzle fails entirely to operate, the quantity of fuel supplied by the auxiliary nozzle may be increased by opening the air admitting screw of the receptacle for this nozzle and letting thus a higher pressure, for instance, atmospheric pressure act upon the fuel contained in this receptacle. In the latter case the auxiliary nozzle will operate, like the main nozzle, solely under the action of the partial vacuum existing in the suction pipe.

In order to make my invention clear, I refer to the accompanying drawings, in which:

Figure 1 is a vertical section through the carbureter on line A—A of Fig. 4. Fig. 2 is a vertical section on line B—B and Fig. 3 is a section on line C—C of Fig. 4. Fig. 4 is a horizontal section on line D—D of Fig. 1.

Referring to the figures of the drawing, *a* is the main nozzle fed from the main receptacle, *b* by means of a channel *c*. A float *d* in this receptacle is weighted by means of the weights *e* provided with suitable levers which are adapted to move downwardly with the float during the sinking of the level of the fuel and raise thereby the valve rod *f* for opening the fuel valve in order to replenish the fuel consumed. As soon as the level of the liquid has reached a predetermined height, for instance as shown, the float has been correspondingly raised and the valve rod *f* has been lowered so as to close the valve and interrupt the inflow of the fuel.

In the cover of the receptacle *b* an air vent *g* is provided. The fuel within the receptacle *b* therefore will be kept under atmospheric pressure. The fuel therefore will leave the spray nozzle *a* under a pressure equal to the preponderance of the atmospheric pressure over the pressure existing in the suction channel.

The auxiliary nozzle *h* is connected by means of a conduit *i* with the auxiliary receptacle *k* containing a float *m* and receiving its fuel supply through a channel *l* from the main receptacle *b* (Fig. 3). The float *m* in the receptacle *k* is connected by means of a rod *t* to a valve *v* controlling the fuel supply from the receptacle *b* to the receptacle *k*. Under normal conditions this valve *v* is kept closed and therefore the fuel supply is cut off. As the fluctuations of the level of the fuel within the auxiliary receptacle *k* wholly depend upon the weight of the float *m*, it will be clear that by suitable selections of this weight the height of the level of the fuel in the auxiliary receptacle *k* can be kept lower than the level of the fuel in the main receptacle *b*.

The air space in the receptacle *k* is connected through the channel *n* with the suction channel. The auxiliary receptacle *k* and the auxiliary nozzle *h* therefore represent a system of communicating pipes standing under the suction or lower pressure.

If the air nozzle *s* would not be provided it would be impossible to spray the fuel through the auxiliary nozzle *h*. It will therefore be clear that only the current of air issuing through the nozzle *s* will be the agent for causing an outflow of the fuel from the auxiliary nozzle *h*, because this air current will exert a suction upon the fuel within the auxiliary nozzle *h* in the same manner as the blow tube of an inhaler of known construction acts upon the liquid container. The pressure prevailing in the auxiliary receptacle *k* will tend to produce a rise of the fuel within the auxiliary nozzle *h*, and thus materially facilitate the inhaling effect and increase the quantity of fuel exhausted through said nozzle. The wider the air inlet *p* is opened by the proper manipulation of the slide *o* the more will the surplus of pressure preponderate over the inhaling action for forcing the fuel through said nozzle and finally said inhaling action will be entirely overcome by the pressure and the nozzle will operate in the manner of an ordinary spray nozzle as for instance the nozzle *a*. In order to permit the regulation of the fuel fed through the auxiliary nozzle *a* an air admitting screw *o* is provided at the upper part of the receptacle *k*. By means of this screw *o* the width of the air inlet *p* can be regulated at will. If by properly regulating said screw atmospheric air is allowed to enter the receptacle *k*, a constant increase in pressure in said receptacle will be generated which is greater than that prevailing in the suction conduit. It is true that the part of the atmospheric air entering through the inlet *p* will flow off through the channel *n* however; as said channel is much smaller than the channel *p* the loss of air led off through said channel is practically insignificant. If the auxiliary nozzle *h* has the same diameter as the main nozzle *a*, both nozzles will operate uniformly for spraying the same amount of fuel if the air admitting screw *o* is manipulated so as to fully open the air inlet *p*.

What I claim is:

1. In a spray carbureter, the combination, with a main receptacle for containing liquid fuel under atmospheric pressure, a float in said liquid within said receptacle, a nozzle connected with and supplied with fuel from the said receptacle; and with another receptacle for containing liquid fuel under a different pressure from that existing in the suction pipe, a float in this liquid within this receptacle, an auxiliary nozzle connected with and supplied with liquid fuel from said other receptacle; of a third nozzle adapted to produce a jet of air or the like when exposed to the sucking action of the motor; the end of the said auxiliary nozzle being arranged at an angle with regard to the end of said third nozzle and behind the same with respect to the direction of the jet of air or the like, for the purpose as described.

2. In a spray carbureter, the combination, with a main receptacle for containing liquid fuel under atmospheric pressure, a float in said liquid within said receptacle, a nozzle connected with and supplied with fuel from the said receptacle; and with another receptacle for containing liquid fuel under a different pressure from that existing in the suction pipe, a float in this liquid within this receptacle, an auxiliary nozzle connected with and supplied with liquid fuel from said other receptacle; of a third nozzle adapted to produce a jet of air or the like when exposed to the sucking action of the motor; the end of the said auxiliary nozzle being arranged at an angle with regard to the end of said third nozzle and behind the same with respect to the direction of the jet of air or the like.

In testimony whereof I have signed my name to this specification in the presence of two witnesses.

MAX BUCHERER.
